[57] CLAIM

The ornamental design for door hutch, as shown and described.

DESCRIPTION

FIG. 1 is a front elevational view of a door hutch showing our new design;

FIG. 2 is a right side elevational view, the left side being a mirror image thereof;

FIG. 3 is a top plan view thereof;

FIG. 4 is an enlarged fragmentary sectional view taken along line 4—4 of FIG. 1;

FIG. 5 is an enlarged fragmentary sectional view taken along line 5—5 of FIG. 1; and

FIG. 6 is an enlarged fragmentary sectional view taken along line 6—6 of FIG. 1.

FIG. 1

FIG. 2

FIG. 3

FIG. 4

FIG. 5
